UNITED STATES PATENT OFFICE.

FLORENCE M. HARRIS, OF BROOKLYN, NEW YORK.

BED.

1,103,765.

Specification of Letters Patent. Patented July 14, 1914.

Application filed May 2, 1914. Serial No. 835,855.

To all whom it may concern:

Be it known that I, FLORENCE M. HARRIS, a citizen of the United States, residing at Brooklyn, in the county of Kings and State 5 of New York, have invented certain new and useful Improvements in Beds, of which the following is a specification.

This invention relates generally to beds, and more particularly to one of that type 10 used in hospitals.

As is well known, patients in hospitals are generally removed from their beds once in twenty-four hours in order to permit the mattress to be turned so as to render it more 15 comfortable to the occupant, and also as a sanitary measure. To accomplish this requires the wheeling alongside of the occupied bed of a second bed upon which the patient is lifted, after which the mattress 20 on the bed occupied is turned, and the patient again placed thereon. This procedure is laborious to the attendants, irksome and oftentimes painful to the patient, owing frequently to the inequality in the height of the 25 two beds, and further, the noise attending the positioning and removal of the supplemental bed is a source of annoyance to patients who are nervous.

It is the object of the present invention 30 in a ready, thoroughly efficient and practical manner to combine a supplemental mattress frame with the bed in such a manner as to permit of its being readily brought to position to receive a mattress upon which 35 the patient may be disposed while that before occupied is turned, the supplemental mattress being adapted readily and easily, when its use is finished, to be slid under the bed proper, and thus out of the way.

With the above and other objects in view, 40 as will appear as the nature of the invention is better understood, the same consists in the novel arrangement and combination of parts of a supplemental mattress frame and mattress for hospital beds, as will be hereinafter fully described and claimed.

In the accompanying drawings forming a 45 part of this specification, and in which like characters of reference designate corresponding parts: Figure 1 is a side elevation of a bed equipped with the improvement of the present invention; the supplemental mattress being lifted to receive a patient; Fig. 2 is a similar view showing the supplemental mattress in folded position; Fig. 3 is a view in end elevation of a bed with the

supplemental mattress applied thereto, and showing the same in position to receive the patient; Fig. 4 is a top plan view, on an enlarged scale, partly in section, exhibiting 60 certain features not clearly shown in the other views. Fig. 5 is a fragmentary detail view.

Referring to the drawings, 1 designates the head piece of a bed, 2 the foot piece and 65 3 the side rails of the mattress proper. These parts may be of the usual or any preferred construction, but are preferably of metal, on account of its sanitary qualities, and the ease with which it may be cleansed and 70 maintained free from noxious germs.

Combined with one of the vertical head and foot pieces, on the same side of the bed, is the supplemental mattress that constitutes the gist of the present invention. This mattress 75 consists of a rectangular frame comprising side rails 4 and 5, and end rails, 6 and 7, the rails being secured at their corners by triangular brace plates 8 that are rigidly riveted to the upper faces of the 80 mattress frame. The mattress is herein shown as constructed of thin strips of metal 9, which are riveted to the rails and are interwoven in such manner as to present a 85 resilient and smooth surface for receiving a supplemental mattress upon which the patient will be placed while the mattress on the bed proper is being turned or changed.

The means for combining the end rails 6 and 7 with the two vertical posts referred 90 to, consists of a clip, each of which is a counterpart of the other, so that a description of one will serve for both. Each clip comprises a band 10 that is designed to surround the vertical post, one side 11 of the 95 clip being straight, and the other side 12 curved around the post, and in close contact therewith, thence bent inward to form a neck 13 which is secured to the member 11 by a rivet 14. The side 12 from the neck is 100 disposed at right angles from the member 11, and terminates in a yoke 15, and pivotally connected to the yoke is the shank 16 of a second yoke 17 which is pivotally connected at 18 with the under flange of the end 105 rail of the supplemental mattress frame. This end rail is provided at its inner end with an approximately hook-shaped lug 19 that is designed to engage a slot or seat 19^a formed in the post, so that when the mattress 110 is moved to the position shown in Fig. 1, there will be no danger of the frame becom-

ing disconnected from the head and foot pieces of the bed. As above stated, this arrangement is the same at both ends of the bed, and its operation will therefore be 5 readily understood.

Pivottally connected with the front side rail of the supplemental frame are two legs 20, the ends of which are provided with rubber cushions 21, and each of these legs carries 10 a spring pressed pin 22 that is designed to engage an orifice 23 formed in the adjacent side rails, the object of these catches being to hold the legs assembled with the front side rails when the bed is moved to 15 the position shown in Fig. 2, that is, under the mattress of the bed proper, and at a sufficient distance below the same to preclude any interference between the two parts when the supplemental mattress is being 20 positioned.

In order to permit inward and outward sliding movement of the supplemental mattress relative to the main mattress, the side flanges of the end rails of the supplemental 25 mattress are provided with longitudinal slots 24 in which the pins 18 are free to slide, so that when the mattress is turned out it may be swung upward and then inward to bring the lugs into engagement 30 with the orifices in the vertical posts of the head and foot piece, and thus lock the supplemental mattress in position, the rubber cushions on the lower ends of the legs serving 35 to hold them against slippage on the floor.

From the foregoing description it will be seen that although the improvements herein described are simple in character, that they will be thoroughly efficient for the purposes 40 designed, and will coact in the presentation of a sanitary and thoroughly reliable form of supplemental mattress support for beds.

While the invention is described more 45 particularly as combined with a hospital cot or bed, it is to be understood that the invention is clearly adaptable to beds of any character, and as this will be readily understood, detailed illustration of any 50 modified form of bed is omitted.

I claim:

1. The combination with a bed frame embodying a mattress proper of a supplemental mattress frame occupying a position normally beneath the mattress proper, and 55 pivoted members connected with the bed frame and having a sliding engagement with the supplemental mattress frame whereby the latter may be swung upward to occupy a plane parallel with the mattress 60 proper.

2. The combination with the head and foot piece of a bed, of clips secured thereto each embodying a yoke, a second yoke carried by each of the first named yokes, a supplemental mattress frame having a sliding 65 connection with the two second yokes, and pivoted legs carried by the front rail of the supplemental frame and foldable upwardly thereagainst.

3. The combination with the head and foot piece of a bed, of clips secured thereto each embodying a yoke, a second yoke carried by each of the first named yokes, a supplemental mattress frame having a sliding 75 connection with the two second yokes, pivoted legs carried by the front rail of the supplemental frame and foldable upwardly thereagainst, and means for holding the legs secured to the side rail.

4. The combination with the head and foot piece of a bed, of a clip secured to vertical posts of each of the pieces and embodying a yoke, a second yoke having a pivotal connection with each of the first named 85 yokes, a supplemental mattress frame having a sliding connection with the two second yokes, whereby to permit of the supplemental mattress frame being swung upward to bring it to load receiving position, 90 and downward to pass under the mattress proper of the bed, and hinged legs carried by the front side rail of the supplemental mattress frame.

In testimony whereof I affix my signature 95 in presence of two witnesses.

FLORENCE M. HARRIS.
